UNITED STATES PATENT OFFICE.

REGINALD E. DAVIS, OF HAYWARD, WISCONSIN.

FURNACE.

SPECIFICATION forming part of Letters Patent No. 672,595, dated April 23, 1901.

Application filed July 31, 1900. Serial No. 25,399. (No model.)

To all whom it may concern:

Be it known that I, REGINALD E. DAVIS, a citizen of the United States, residing at Hayward, in the county of Sawyer and State of Wisconsin, have invented certain new and useful Improvements in Furnaces, of which the following is a specification.

My invention relates to improvements in furnaces designed especially for burning saw-dust, its object being to provide means for causing more perfect combustion of the fuel and more perfect control of the fire than in the ordinary construction.

To this end my invention consists in the improvements in the grate and attachments hereinafter specifically described and claimed.

In the accompanying drawings, forming part of this specification, Figure 1 is a broken-away perspective view showing the grate and the supporting devices therefor. Fig. 2 is a detail view of the grate-support and air-supply device. Fig. 3 is a side elevation of a grate-bar, and Fig. 4 is a bottom view of the bar.

25 In the drawings, A represents a furnace of ordinary construction provided with the fire-box opening 2. Arranged within the fire-box opening is a dome-shaped grate B, made up of the grate-bars 3. The bottom of each of

30 these grate-bars rests upon a ring 4, which in turn rests upon the ledge 5 of the fire-box. The grate-bars are tapered toward their upper ends to form a dome-shaped grate, as shown in Fig. 1. The upper ends of the grate-bars rest upon the top of the central supporting device C. This device is made up of a hollow standard open at its lower end and carrying a detachable top piece 6, provided with perforations 7. The standard is prefer-

35 ably provided with a central perforate section 8 and is supported by legs 9, carried by the flaring bottom 10 of the standard. The ring 4, which rests upon the ledge 5 and supports the grate, may be of any desired construction and made in one or several pieces, as may be desired. By having the grate of the dome shape shown the sawdust is distributed over a large area and is supplied with a greater quantity of air than in the ordinary construction. By having the central

supporting-standard hollow and perforated at its top air is allowed to pass to the top of the grate-bars, keeping the same from warping. The perforations 8, which are arranged in the standard below the grate, will allow a 55 current of air through the standard in case the bottom of the standard becomes closed by ashes in the ash-pit.

The furnace has only been shown conventionally in the drawings, and it is evident that it can be changed without departing from the idea of my invention. The fire-box is preferably circular, but may be of any desired shape.

While my invention is designed particularly for the burning of sawdust, it may be used for the burning of any other suitable fuel.

I claim—

1. In a furnace of the class described, the 70 combination with the fire-box, of a dome-shaped grate arranged therein, a central supporting-standard resting at its lower end upon the base of the furnace and abutting at its upper end against the top of the dome to 75 serve as a support therefor, said standard being perforated at its upper end and being open at its lower end some distance above the base of the furnace.

2. In a furnace of the class described, the 80 combination with the fire-box, of a dome-shaped grate therein, and a central supporting hollow standard therefor, said standard being open at both ends and provided with perforations in its wall below the grate. 85

3. In a furnace of the class described, the combination with the fire-box, of a dome-shaped grate supported therein, a central hollow supporting-standard for said grate, the lower end of said standard being open 90 and the upper end perforated, said standard having perforations in its wall below the grate.

In testimony whereof I affix my signature in presence of two witnesses.

REGINALD E. DAVIS.

Witnesses:

SAM J. WILLIAMS,
B. W. SKEEDER.
